(57) **CLAIM**

The ornamental design for a quick release design, as shown and described.

DESCRIPTION

FIG. 1 is a perspective view of the quick release design showing my new design.

FIG. 2 is a rear view thereof;

FIG. 3 is a top plan view thereof;

FIG. 4 is a left side view thereof;

FIG. 5 is a front elevation view thereof;

FIG. 6 is a right side view thereof;

FIG. 7 is a bottom plan view thereof;

FIG. 8 is a front elevation view shown in use; and,

FIG. 9 is another front elevation view shown in use.
The broken lines in the drawings are for illustrative purposes
of the environment only and form no part of the claimed
design.
